United States Patent Office

Des. 229,798
Patented Jan. 8, 1974

229,798

CHAIR

Jerry E. Howard, 1091 S. Towne,
Pomona, Calif. 91767

Filed Mar. 1, 1972, Ser. No. 231,060

Term of patent 14 years

Int. Cl. D6—01

U.S. Cl. D6—26

FIG. 1.

FIG. 2.

FIG. 3.

FIG. 4.

FIG. 5.

FIG. 1 is a right side elevational view of a chair, showing my new design;

FIG. 2 is a front elevational view thereof;

FIG. 3 is a rear elevational view thereof;

FIG. 4 is a top plan view thereof; and

FIG. 5 is a bottom plan view thereof.

The side not shown is a mirror image of the side shown in FIG. 1.

I claim:

The ornamental design for a chair, as shown and described.
